UNITED STATES PATENT OFFICE.

FREDERICK B. LITTLE, OF CHICAGO, ILLINOIS, ASSIGNOR, BY MESNE ASSIGNMENTS, TO
J. C. DEAGAN MUSICAL BELLS, OF CHICAGO, ILLINOIS, A CORPORATION OF ILLINOIS.

ELECTRIC SWITCHING MECHANISM.

1,228,222,

Specification of Letters Patent.

Patented May 29, 1917.

Application filed March 13, 1916. Serial No. 83,774.

To all whom it may concern:

Be it known that I, FREDERICK B. LITTLE, citizen of the United States, residing at Chicago, in the county of Cook and State of Illinois, have invented a certain new and useful Improvement in Electric Switching Mechanism, of which the following is a full, clear, concise, and exact description, reference being had to the accompanying drawings, forming a part of this specification.

My invention relates to electric switches and is of particular service when employed in keyboard musical instruments having sound producing devices that have electro-magnets for effecting their operation and has for its object the provision of improved switching mechanism that is operable by the keys and whereby injured switches may readily be removed and replaced without dismounting the keys. The importance of my invention will be appreciated when it is understood that switches frequently break down during a musical performance, hitherto requiring much time in repair whereas by the device of my invention an injured switch may be instantly replaced.

In the preferred embodiment of the invention I provide a mounting strip at the rear of the keyboard, this mounting strip carrying a plurality of pairs of serially related contacts, there being one pair of such contacts individual to each sound producing device. Each pair of contacts has a pair of serially related complementary contacts, the pairs of complementary contacts being mounted upon separate carriers. The contacts of each pair has separable engagement with the contacts of the pair complementary thereto, a plug and jack formation of the interengaging contacts being preferably employed whereby the pair of complementary contacts mounted upon separate carriers may readily be engaged with the contacts carried by the mounting strip. Each key has a pair of separable contacts individual thereto and carries a switch operator for bringing such contacts electrically together, this switch operator being desirably in the nature of a stiff leaf spring operating upon one contact

to force it against its companion, the first contact being desirably in the form of a leaf spring which will automatically separate from its companion when the corresponding key is released.

I will explain my invention more fully by reference to the accompanying drawings showing the preferred embodiment thereof and in which Figure 1 diagrammatically illustrates the preferred embodiment of the invention; Fig. 2 is a plan view of a part of a bank of keys and associated switching mechanism; and Fig. 3 is a sectional view on line 3—3 of Fig. 2.

Like parts are indicated by similar characters of reference throughout the different figures.

The sound producing devices illustrated in Fig. 1 include each an operating magnet 1 adapted for inclusion in bridge between the sides 2 and 3 of a supply circuit furnished with current by a battery 4 also in bridge between these sides. Each magnet containing bridge may be traced from the side 2 of the supply circuit through the contact 5, the contact 6 normally engaging contact 5, the winding of the magnet, the contact screw 7, the contact thimble 8 into which the screw is threaded (this contact thimble constituting a jack), a split pin 9 constituting a plug for reception within the jack 8, the leaf spring 10, a contact 11 complementary to the spring 10 and from which the spring 10 is normally separated due to the resilience of such spring, a screw 12, a contact thimble 13 into which the screw 12 is threaded (this contact thimble constituting a jack), a split pin 14 constituting a plug for reception within the jack 13, to the other side 3 of the supply circuit. The conductors which lead from the magnets 1 to the screws 7 are included in a cable 15 that is disposed beneath a mounting strip, this mounting strip being separably secured to the back of the keyboard cabinet by screws 17. The contacts 8 and 14 are mounted upon the mounting strip 16, the contacts 14 being in common connection as they are desirably mounted upon a conducting strip 18. The contacts 8, however, are electrically separate,

being individual to the magnets 1 and the sound producing bars 19 individual to such magnets and operated upon by the hammers 20 carried by the magnet armatures. The 5 pair of contacts complementary to each pair of contacts 8 and 14 is mounted upon an insulating carrier 21, each of these pairs of complementary contacts 9 and 13 being mounted upon a separate carrier whereby 10 any pair of complementary contacts may be readily separated from the mounting strip and the contacts they engage. The electrical continuations 10 and 11 of the contacts 9 and 13 are, of course, bodily movable with 15 the contacts 9 and 13 as they are mounted upon the same carrier. These elements 10 and 11 themselves constitute a switch, such switches projecting, at their forward ends, over the rear ends of the manual keys 22 20 which are desirably black and white and correspond in arrangement to the keys of a piano. Each manual key 22 carries a switch actuator or operator 23 that is desirably in the form of a stiff spring finger terminating 25 at its upper end beneath and in contact with the spring contact 10, the arrangement of the parts being such that the spring contact 10 will disengage itself from the contact 11 when the associate key 22 is in normal position 30 or is not sufficiently depressed to cause the finger 23 to move the contact 10 into engagement with the contact 11. The spring 10 also desirably exerts restoring force upon the key 22 underlying it though this function 35 is preferably supplemented by the action of an additional spring 24. The rear ends of the manual keys and the switching mechanism are normally covered by the hinged lid 25 that may be swung back when 40 access is to be had to the switching mechanism.

The operation of the instrument will be readily understood from the foregoing description of the drawings. The sound producing bars 19 are individual to different keys 22 and the magnets 1 to which such keys are individual and as these bars are desirably arranged in a chromatic scale sufficient depression of the keys will cause the 45 corresponding bars to vibrate in the order in which the keys are operated. Hitherto the switches controlled by the keys have been so mounted as to render them difficult of access and as to require much time to 50 effect their removal and replacement so that if any of the switches broke down during a performance such performance would likely have to be discontinued. If the contacts 10 and 11 of any switch should become injured 55 as a consequence of sparking or otherwise, the carrier 21 for such contacts may be quickly removed and a new carrier with similar contacts may readily be put into the position of the removed carrier with the

contacts 9 and 13 engaging the fixed contacts 8 and 14.

While I have herein shown and particularly described the preferred embodiment of my invention I do not wish to be limited to the precise details of construction shown 70 as changes may readily be made without departing from the spirit of my invention, but having thus described my invention I claim as new and desire to secure by Letters Patent the following:

1. The combination with a bank of manual keys; of switches, each individual to a manual key and located over the rear end thereof and having a movable contact-member interposed between the key and the contact complementary to such contact-member; switch-actuating members upon the keys and projecting upwardly into engagement with said movable contact-members and serving to bring these movable contact-members into engagement with their complementary contacts when the keys are depressed; individual carriers for said switches; a mounting for said carriers; and connecting switches for connecting the aforesaid switches and having separable complementary parts upon the mounting and carriers.

2. The combination with a bank of manual keys; of switches, each individual to a manual key; switch actuating members upon the keys and engaging movable members of the switches; individual carriers for said switches; a mounting for said carriers; and connecting switches for connecting the aforesaid switches and having separable complementary parts upon the mounting and carriers.

3. The combination with a bank of manual keys that are each individual to a sound producing device; of switches; each individual to a manual key and operable thereby; individual carriers for said switches; a mounting for said carriers; and connecting switches having separable complementary parts upon the mounting and carriers.

4. The combination with a bank of manual keys that are each individual to a sound producing device; of switches, each individual to a manual key and operable thereby; individual carriers for said switches; and means whereby said carriers are separably mounted to enable the switches readily to be dissociated from the keys.

5. The combination with a bank of manual keys; of switches, each individual to a manual key and located over the rear end thereof and having a movable contact member interposed between the key and the contact complementary to such contact member; switch actuating members upon the keys and projecting upwardly into engagement with said movable contact members and serving

to bring these movable contact members into engagement with their complemental contacts when the keys are depressed; individual carriers for said switches; and a mounting for the carriers upon which such carriers are separably supported.

5. In witness whereof, I hereunto subscribe

my name this twenty-sixth day of February, A. D. 1916.

FREDERICK B. LITTLE.
